WINDING OF YARN OR THREAD PACKAGES

Allan Hinds Tidmus, Spondon, near Derby, England, assignor to Celanese Corporation of America, a corporation of Delaware

Application October 29, 1930, Serial No. 491,888,
and in Great Britain January 3, 1930

5 Claims. (Cl. 118—62)

This invention relates to the production of twisted yarn or thread, and has for its object an improved method of forming packages of twisted yarn or thread in cap-spinning operations.

6. Hitherto, in the production of packages of twisted and wound thread by means of cap-spinning devices, the thread has usually been laid on the bobbin with a slow traverse from one end of the bobbin to the other, this traverse being effected by relative motion in the direction of the bobbin axis between the cap and the bobbin. In the case of threads fed to the bobbin at a high linear speed, the package-building traverse along the bobbin axis is so slow relatively to the rate at 10 which the thread is wound on the bobbin that each thread turn is practically in a plane at right-angles to the bobbin axis, i. e. substantially "parallel" winding results. In this form of package the turns of each layer are substantially 15 parallel to the turns of the layer beneath, and trouble has been experienced from the fact that the turns of thread tend to slip in between the turns of the layer beneath, and to become jammed there. This is especially the case with dry-spun 20 artificial threads which are produced and wound at a high linear speed, and, further, are of a smooth and slippery nature, which allows the turns to slip easily between the turns over which they are wound. The result is that the jammed 25 30 thread tends to break during subsequent unwinding operations, causing delay and wastage of the thread.

Building of the package by cross winding, i. e. traversing the thread along the bobbin sufficiently 35 rapidly to obtain a wind wherein each turn of thread crosses the turns of the layer beneath at an appreciable angle would, of course, avoid the difficulty, but it is not convenient to employ the rapid traverse necessary to give the cross-wind in 40 twisting and winding operations in which threads are delivered to the twisting device at a high linear speed.

The object of the present invention is to build a thread package in the course of a cap-spinning 45 or like twisting and winding operation, which package possesses the advantages of a cross wound package, without resorting to the rapid traversing necessary to produce a true cross-wind.

According to the present invention a small 50 cross-wind effect is imparted to a thread in a twisting and winding operation by causing the point of contact of the thread with means serving to guide the thread on to the package to follow an oscillating motion in the direction of the axis of 55 the package as the said point of contact describes

an orbital path around the package, so that each turn of the thread bears over and secures the preceding turn. Thus, the point of contact of the thread with the edge of a cap-spinning device, from which the thread is guided to the package, may oscillate up and down in the direction of the axis of the package, such oscillation occurring at least once in each revolution of the said point of contact in its orbit round the package. For example, there may be used a cap whose edge is 60 formed otherwise than in a plane at right-angles to the axis of the cap. The thread is laid on the bobbin from successive points along the cap edge, and according as these points occupy a higher or lower position with respect to the bobbin so is the 65 thread laid at a higher or lower position on the 70 bobbin.

The package produced in this way consists of 75 layers of thread, each turn of which is of an undulatory character, several oscillations or waves of small amplitude occurring in each turn. The amplitude of the oscillations will be smaller than the amplitude of the oscillation of the means for guiding the thread on to the bobbin to an extent depending on the distance of the 80 said means from the thread surface on the bobbin. The length of each oscillation or wave will also be small, being equal at the most to the length of thread laid on the bobbin during the 85 time in which the thread revolves around the bobbin axis. At least one oscillation will occur for each twist of the thread and several twists generally occur in each turn of thread laid on the bobbin. The oscillations in the thread turns, though small in amplitude are, however, sufficient 90 to cause the turns to cross those of the layer beneath, so preventing them from slipping between the previous turns. If the speed at which the thread is fed to the bobbin is comparatively low, each turn of a layer will be separated somewhat 95 from adjacent turns of the same layer, but if the speed of feeding is high, the turns of each layer may be sufficiently close together that, by reason of the oscillations or waves in the turns, each turn overlaps one or more previous turns 100 of the same layer along some part of its length.

The invention is particularly applicable to the winding and twisting of yarns or threads continuously with their production, and is especially applicable to the winding and twisting of artificial yarns, filaments or threads produced by the dry or evaporative method.

The invention will now be described in greater detail with respect to the accompanying drawing, but it is to be understood that the following de- 110

scription is given by way of example only and is in no way limitative.

Fig. 1 is a front elevation of a cap-spinning device according to the invention, showing the manner in which the thread is wound on to the bobbin;

Fig. 2 is a side elevation of the cap-spinning device shown in Fig. 1; and

Fig. 3 is a representation to an increased scale 10 of the winding effect produced.

The apparatus employed for production of the thread may conveniently be of the type described in U. S. Patent No. 1,731,317, the thread of filaments of cellulose acetate or other cellulose derivative being led from the spinning cell, passed over suitable lubricating or other wicks, if desired, and round a feed roller or godet to a balloon guide, from which guide it is led to a cap-spinning device as shown in Figs. 1 and 2.

20 In Fig. 1, the thread 6 passing to the package 7 passes over the annular edge 8 of a spinning cap 9, which edge 8 instead of being in a plane at right-angles to the axis of the package 7, is inclined to that axis to such an extent that one side of the edge is at a height of, say, $\frac{3}{8}$ " or $\frac{1}{2}$ " above the other. The thread then passes from the edge 8 to the package 7.

30 The package 7 is rotated at a peripheral speed considerably higher than the rate at which the thread 6 is delivered to the bobbin and the thread is thus caused to rotate as a "balloon" round the cap 9, the drag imposed by the resistance of the air and by friction with the cap edge 8 causing the balloon to lag behind the bobbin somewhat 35 to cause the thread which has been twisted by its rotation to be laid on the package 7.

40 During each revolution of the thread 6 around the cap 9 the point of contact of the thread 6 with the edge 8 of the cap makes a complete oscillation in a vertical direction, while a small length of the twisted thread is laid on the package. This length takes a wavy form as shown by the full line 10 and overlaps the turns of thread in the layer beneath, one turn of which is shown 45 by the dotted line 11, any tendency of the length 10 to slip between the lower turns thus being overcome. This wavy or undulatory winding is additional to the normal traversing wind which is also shown by a slight inclination of the thread 50 from left to right.

55 Instead of the edge of the cap lying in a plane inclined to the axis of the cap, it may have any other suitable form adapted to cause the thread to oscillate. One such form is shown by the dotted line at 12 in Fig. 1, the edge of the cap continuing almost horizontally from its lowest point, then rising fairly steeply, and finally running almost horizontally to its highest point.

60 The traversing movement of the package 7 is arranged so that the upper edge of the lower flange of the bobbin is level with the mean height of the cap edge when the bobbin is in its lowermost position in order to secure even building of the thread package, and although the lowest

point of the edge comes below the level of the upper surface of the flange at the lowest portion of the bobbin, the thread is swept cleanly over the surface of the flange on to the package. It is necessary however, to have a smooth flange free from projections and preferably the flange has a turned-over brass or other metal cover whose edge is pressed into the body of the flange.

80 The balloon guide 14 from which the thread passes to the cap edge may be placed vertically above the cap spindle, or, in order to maintain the balloon uniform and to avoid tension fluctuations, the guide may be displaced to a point 15 in or towards the axis of the plane bounded by the cap edge.

85 In Fig. 3, which shows to an increased scale the manner in which the thread is wound on to the bobbin, the turn of thread being wound is shown by the full line 10 and it will be seen that this turn overlaps the turns of the preceding layer, one such turn being shown by the dotted line 11. The next winding turn 20 of thread immediately following the turn 10 is shown in broken chain line and overlaps the turn 10 90 of the same layer as well as turns 11 of the preceding layer.

95 What I claim and desire to secure by Letters Patent is:—

1. Cap-spinning apparatus for winding packages of threads having a cross wind effect, comprising a spindle adapted to carry a rotatable tube bearing a package support, and a cap adapted to fit over said spindle so as to depend round said package support, said cap having a lower edge which as a whole does not lie in a plane at right angles to the axis of rotation of the package.

105 2. Cap-spinning apparatus for winding packages of threads having a cross wind effect, comprising a spindle adapted to carry a rotatable tube bearing a package support, and a cap adapted to fit on said spindle so as to depend round said package support, said cap having a lower edge which as a whole does not lie in a plane at right angles to the axis of the cap.

115 3. Cap-spinning apparatus for winding packages of threads having a cross wind effect, comprising a spindle adapted to carry a rotatable tube bearing a package support, and a cap adapted to fit over said spindle so as to depend round said package support, said cap having a lower edge lying in a plane inclined to the axis of the cap.

125 4. A cap for cap-spinning apparatus comprising a tubular member open at one end, said end terminating in an annular edge which as a whole does not lie in a plane at right angles to the axis of the cap.

130 5. A cap for cap-spinning apparatus comprising a tubular member open at one end, said end terminating in an annular edge lying in a plane inclined to the axis of the cap.
